UNITED STATES PATENT OFFICE

WALTER MYERS, OF BRIDGEPORT, CONNECTICUT, ASSIGNOR TO THE SINGER MANUFACTURING COMPANY, OF ELIZABETH, NEW JERSEY, A CORPORATION OF NEW JERSEY

SEWING MACHINE

Application filed December 20, 1929. Serial No. 415,449.

This invention relates to improvements in work-guiding and feeding devices for sewing machines and has for its object to provide simple and efficient means for attaching bead-chains and equivalent articles to body-materials for purposes of ornamentation or reinforcement.

As commonly constructed, the beads and bead-connecting links of a bead-chain are relatively movable to a limited extent in a direction lengthwise of the chain. It has been a prior practice to attach a bead-chain along the edge of a body-material by means of a zigzag-stitch sewing machine, with the intended object of having the zigzag-stitches successively formed across the chain-links between successive beads of the chain. However, because of the relatively movable character of the chain-beads and the inclination of the zigzag-stitches with respect to the direction of the chain-length, it has heretofore proven practically impossible to attach bead-chains to body-materials, under commercial conditions of high speed of operation of the machine, without frequently skipping a bead-link and thereby marring the appearance and impairing the strength of the product.

According to the present invention, a bead-chain is secured to a body-material margin by pairs of substantially parallel stitches crossing each of the chain-links between successive chain-beads, said pairs of stitches being substantially normal to the length of the chain and joined by connecting stitches anchored in the body-material. This attaching seam provides for freedom of movement of the chain-beads to an extent necessary to obviate distortion of a curved body-material margin to which the chain is attached and also greatly simplifies the problem of preventing the undesirable skipping of any of the bead-links.

In order to attach bead-chains to body-materials in the present improved manner, there is preferably employed a sewing machine having stitch-forming mechanism including an endwise reciprocating and laterally vibratory needle and a feeding mechanism imparting advancing movements to the work of less frequency than the endwise reciproca-

tions of the needle. The sewing machine is provided with guiding means for directing an edge of the body-material and a bead-chain in juxtaposed relation within the range of lateral vibration of the needle. The feeding mechanism includes a feed-dog engaging the bead-chain substantially at or rearwardly of the needle and which feeds the chain-beads slightly faster than the advancing movement of the body-material, thereby slightly crowding the chain-beads together for the purpose of rendering the chain extensible and capable of adapting itself to curved body-material margins.

Bearing upon the body-material adjacent the needle is a presser-member which is yieldingly mounted independently of an auxiliary presser-member yieldingly engaging the chain-beads. In the preferred embodiment of the sewing machine fittings, said bead-chain feeding means and auxiliary presser-member are so constructed as to clamp the bead-chain upon the work-support between advancing movements of the bead-chain, the presser-member being lifted clear of the portion of the bead-chain in advance of the needle each time that a bead of said chain is advanced by the feeding mechanism. In order to prevent crushing of the chain-beads between the feed-dog and the end wall of the feed-slot in the throat-plate there is provided a chain-guard which in a preferred embodiment comprises a spring-plate secured upon the throat-plate in position to partially enter the throat-plate feed-slot and yieldingly bear upon the feed-dog beyond its rearward tooth.

In the accompanying drawings, Fig. 1 is a longitudinal section, partly in front elevation, of a sewing machine containing a preferred embodiment of the present improvement. Fig. 2 is a bottom plan view of the machine. Fig. 3 is a top-plan view of the portion of the sewing machine cloth-plate surrounding the stitching point, including a top-plan view of the auxiliary presser and a portion of the work. Fig. 4 is a sectional view substantially on the line 4-4 of Fig. 3, illustrating the clearance between the auxiliary presser and the unstitched portion of the bead-chain in the raised position of the feed-

dog. Fig. 5 is a perspective view of the feed-dog. Fig. 6 is a perspective view of the front part of the throat-plate. Fig. 7 is a perspective view, partly in section, of a fragment of the product. Fig. 8 is a view in elevation and partly in section of the supporting means for the spring which yieldingly maintains the needle-vibrating bar in contact with its actuating cam.

10 Referring to the drawings, the sewing-machine frame comprises a bed-plate 1, of which the upper side serves as a cloth-plate, and a hollow standard 2 of a tubular bracket-arm 3, terminating in a head 4.

15 Journaled in suitable bearings provided in the bracket-arm 3 is a rotary main- or actuating-shaft 5, carrying at its outer end a combined belt-pulley and balance-wheel 6, and at its opposite end a crank-disc 7 connected in the usual manner by means of a link 8 with a pin 9 projecting from a collar 10 secured upon a needle-bar 11 carrying a needle 12. The needle-bar 11 is journaled for endwise, substantially vertically reciprocatory movements in suitable bearings provided in a swinging frame 13 pivotally supported at its upper end by a fulcrum-stud 14 upon the head 4.

20 The swinging frame 13 is pivotally connected with one end of a vibratory-bar 15, of which the opposite end has an offset arm 16 resting upon a cam 17. The cam 17 is carried by a short shaft 18, journaled in the bracket-arm 3 transversely of the main-shaft 5 and deriving one rotation from said main-shaft 5 to every three rotations of the latter by suitable gear-connections therewith. The arm 16 of the vibratory-bar 15 is yieldingly maintained in contact with the cam 17 by means of a spring 19 coiled about a vertically directed rod 20 of which the lower end has a fork 21 straddling the bar 15 and connected therewith by means of a pivot-bolt 22. The spring 19 is interposed between the fork 21 of the rod 20 and a bearing-washer 23 having a rounded upper end engaging the similarly shaped lower end of a bushing 24, adjustably threaded into an aperture in the bracket-arm 3 and secured by a nut 25. The upper end of the rod 20 is tapered and has sufficient clearance within the bushing 24 to provide for the relatively short, lateral vibrations imparted to the lower end of the rod by the needle-vibrating movements of the vibratory-bar 15, it being understood that the rounded washer 23 is free to rock in its seat in the bushing 24.

25 It is apparent that the cam 17 imparts lateral vibratory movements to the bar 15 about its pivotal connection with the swinging frame 13. These lateral movements of the bar 15 are in part converted, in a well known manner, into endwise reciprocatory movements by pivotally connecting said bar 15 with one end of a link 26 of which the oppo-

site end has a pivotal support 27 constituting a fulcrum for the vibratory-bar 15 as disclosed, for instance, in the patent to C. F. Gray, No. 933,032, dated Aug. 31, 1909.

70 Cooperating with the needle 12 in the formation of lock-stitches is a loop-taker 29 carried by a rotary shaft 30, journaled beneath the cloth-plate and disposed transversely of the path of needle-vibration. The loop-taker shaft 30 carries a bevel-gear 31 in mesh with a similar gear 32 upon one end of a loop-taker actuating shaft 33 of which the opposite end carries a pulley 34 connected by a cleated belt 35 with a driving pulley 36 fixed upon the main-shaft 5.

75 The loop-taker actuating shaft 33 is rotatively journaled within a hollow, feed-lift rock-shaft 37, which is in turn journaled in spaced bearing-lugs, as 38, depending from the bed-plate 1. A crank-arm 39 clamped upon this rock-shaft 37 is connected by a vertically directed link 40 with a rock-lever 41 having a fulcrum 42 upon the bracket-arm 3. The rock-lever 41 has a laterally offset free end 43 carrying a roller 44 tracking a cam-groove 45 provided in the inner side of a cam-disk 46 fixed upon the transverse shaft 18. The action of the cam-groove 45 is to impart only one complete rocking movement to the rock-lever 41, 43 during three complete rotations of the main-shaft 5.

80 The feed-lift rock-shaft 37 also carries a crank-arm 47 suitably engaging one end of a feed-bar 48 of which the opposite end is pivotally connected in the usual manner with a feed-advance rock-shaft 50 journaled in bearing-lugs, as 51 depending from the bed-plate 1. Suitably clamped upon the rock-shaft 50 is a crank-arm 52 pivotally connected with the lower end of a pitman 53 having a strap 54 embracing an eccentric (not shown) adjustably secured upon the main-shaft 5 in any suitable or well known manner. It will be understood from the foregoing description that while the feed-bar 48 receives substantially horizontal, forward and return movements for each complete reciprocation of the needle, it is raised into engagement with the work once only during three complete reciprocations of the needle.

85 90 95 100 105 110 115 120 125 130 Secured upon the feed-bar 48 is a feed-dog 55 having a row of work-engaging teeth, as 56, disposed at one side of the needle-path, the two rear teeth 56' and 56'' which have their work-advancing movement entirely rearward of the needle being widened to extend across the line of seam formation. The feed-dog tooth 56' is in part supported by a stay-bar 57 rising from the front end of the feed-dog 55, the upper side of the stay-bar being disposed below the level of the points of the teeth. The teeth of the feed-dog 55 are intermittently projected through a slot 58 formed in a throat-plate 59 suitably secured upon the cloth-plate 1. Another slot

60 in the throat-plate affords clearance for the stay-bar 57 of the feed-dog, said throat-plate having a needle-slot 61 elongated transversely of the line of seam formation and disposed between the throat-plate slots 58 and 60. Rising from the throat-plate directly in front of the needle-slot 61 is a guide-fin 62 of which one side serves as an edge-guide for a body-material M and the opposite side 10 as a guide for the beads B of a bead-chain. Rearward of the needle-slot 61 the throat-plate is cut away to provide a clearance-slot 63 for the widened feed-dog teeth 56', 56''. Projecting downwardly within the throat-plate slot 63 and bearing upon a ledge 64 upon the feed-dog rearward and below the tooth 56'' is a bead-chain guard comprising in the present instance a spring-plate 65 secured by a screw 66 upon the throat-plate. 15 The free end of the guard 65 rises and falls with the feed-dog of which the ledge 64 slidably engages the guard. This construction prevents entrance of the bead-chain into the throat-plate slot 63 and thereby serves to 20 guard against crushing of the bead-chain between the end of the feed-dog and the rear wall of the feed-slot in the throat-plate. While this guard device is useful in supporting the bead-chain while attaching it to relatively flimsy materials, its primary purpose 25 is to successfully initiate a stitching operation inasmuch as the first bead of the chain is beyond the stitching point when engaged by the feed-dog and is therefore unsupported by stitching.

Opposed to the row of feed-dog teeth 56 is a presser-roller 67 rotatively carried by an arm 68 extending forwardly from a bracket 69 suitably secured upon the usual spring- 30 depressed presser-bar (not shown) journaled for endwise movements in the bracket-arm head 4. This presser-roller yieldingly bears upon the margin of the body-material M, directed by the guide-fin 62, so that the body-material edge crosses the throat-plate needle-slot 61 within the range of lateral vibration of the needle. 35 Yieldingly clamping the bead-chain B against the throat-plate, in the lowered position of the feed-dog, is an auxiliary-presser 40 comprising a bent-plate pivotally supported by pintle-screws, as 71, secured in spaced brackets, as 72 rising from a segment-plate 73 detachably fastened upon the cloth-plate 1. The end of the auxiliary-presser adjacent to the presser-roller 67 is undercut to provide a shoulder 74 defining a chain guideway between said shoulder and the guide-fin 62. The auxiliary-presser is extended beyond its fulcrum to provide convenient means for manually raising the bead-chain engaging end of said presser against the action of a spring 75 interposed between the segment-plate 73 and the extended end of the auxiliary-presser. The work-engaging end of the 45 auxiliary-presser has a needle-slot 76 in front of which the end of said presser is partially cut away so as to be disposed in substantial contact with the bead-chain side of the guide-fin 62, thereby providing a closed guideway 70 for the bead-chain which is automatically directed past the stitch-forming mechanism.

The operation of the machine will be apparent from the foregoing description. The beads B of the bead-chain are regularly constructed so as to be movable to a limited extent lengthwise of the chain-links L. An edge of the body-material M and the beads B of the bead-chain are directed past the stitch-forming mechanism by opposite sides of the 75 guide-fin 62 and when the feed-dog rises, the inclined front side of the feed-dog tooth 56' engages a bead B and slightly advances the bead before the actual feeding of the body-material commences. It will be understood that the bead B engaged between the teeth 56' and 56'' is disposed rearwardly beyond the link L, connected with said bead and secured by stitching before said bead is engaged by the feed-dog. In other words, the 80 advanced bead is rearwardly beyond the stitching point and therefore the advancing or the unstitched portion of the chain is the result of a pulling action thereupon which is unhampered by any pressure upon the unstitched portion of the chain by reason of the fact that the auxiliary-presser is slightly raised above the unstitched portion of the chain by the bead engaged by the feed-dog during its feeding movement. By employing 85 pressers yielding independently of each other in their engagement with the body-material and the bead-chain, the control of the work is unaffected by any difference between the thicknesses of the body-material and the 90 size of the bead-chain.

During the stitching operation, the needle is vibrated to make a pair of stitches S, comprising lateral and return stitches, across each of the chain-links L between successive 95 feeding movements of the work. The needle-path then remains fixed until the work is advanced and a stitch T is made in the body-material, after which the cycle is repeated.

Having thus set forth the nature of the 100 invention, what I claim herein is:—

1. In a sewing machine for attaching a bead-chain to a body material, a work-support, a reciprocatory and laterally vibratory needle, means for advancing the body-material and the bead-chain past the needle including a feed-dog projected through the work-support to engage the chain-beads rearward only of the needle, and presser devices opposed to said work-support bearing upon the body material and bead-chain to yield independently of each other.
2. In a sewing machine for attaching to a body-material a bead-chain having chain-beads movable a limited extent relative to the 105

chain-links in a direction lengthwise of the bead-chain, stitch-forming mechanism including an endwise reciprocatory and laterally vibratory needle, means for feeding the 5 body-material past the stitch-forming mechanism, and means for feeding the chain-beads relatively faster than the advancing movement of the body material.

3. In a sewing machine for attaching a 10 bead-chain to a body-material, stitch-forming mechanism including an endwise reciprocatory and laterally vibratory needle, means for directing an edge of the body-material and the bead-chain in juxtaposed relation 15 within the range of lateral vibration of the needle, and intermittently acting work-feeding means including a feed-dog having work-feeding movements of less frequency than the number of complete reciprocations of the 20 needle.

4. In a sewing machine for attaching to a body-material a bead-chain having chain-beads movable a limited extent relative to the chain-links in a direction lengthwise of the 25 bead-chain, stitch-forming mechanism including an endwise reciprocatory and laterally vibratory needle, means for directing an edge of the body-material and the bead-chain in juxtaposed relation within the range of lateral 30 vibration of the needle, and an intermittently acting feed-dog confined to effective work-feeding movements at every third reciprocation of the needle, said feed-dog acting to advance the chain-beads relatively 35 faster than the body-material.

5. In a sewing machine for attaching to a body-material a bead-chain having chain-beads movable a limited extent relative to the chain-links in a direction lengthwise of the 40 bead-chain, stitch-forming mechanism including an endwise reciprocatory and laterally vibratory needle, means for directing an edge of the body-material and the bead-chain within the range of lateral vibration 45 of the needle, and work-feeding means including a feed-dog having spaced teeth disposed to successively receive therebetween the beads of the bead-chain, said feed-dog having a work-feeding movement of an extent 50 determined according to the maximum spacing of the chain-beads, whereby the beads of the chain are initially engaged by the point of a feed-dog tooth and are advanced relatively to the feed-dog by an inclined side of said tooth during the further 55 bead-engaging movement of the feed-dog.

6. In a sewing machine, a work-support, 60 stitch-forming mechanism including an endwise reciprocatory and laterally vibratory needle, a feed-dog intermittently projected through the work-support, an edge-guide disposed to direct an edge of a body-material within the range of lateral vibration of the needle, a roller-presser opposed to the feed-dog at the body-material side of the edge- 65

guide, and an auxiliary-presser having a bead-chain guideway disposed to direct the bead-chain within the range of lateral vibration of the needle in juxtaposed relation with the edge of the body-material. 70

7. In a sewing machine, a work-support, 75 stitch-forming mechanism including an endwise reciprocatory and laterally vibratory needle, a feed-dog intermittently projected through the work-support, an edge-guide disposed to direct an edge of a body-material within the range of lateral vibration of the needle, a presser opposed to the feed-dog at the body-material side of the edge-guide, an auxiliary-presser having a bead-chain guideway disposed to direct the bead-chain in juxtaposed relation with the edge of the body-material, supporting means upon said work-support for the auxiliary presser, and means for yieldingly urging said auxiliary 80 presser in a direction toward the work-support. 85

8. In a sewing machine having stitch-forming mechanism adapted to attach a bead-chain to a body-material, a work-support, a 90 feed-dog projected through the work-support and provided with two teeth conveniently spaced to receive therebetween during its feeding movement a portion of a bead of the bead-chain disposed upon the work-support 95 in substantially the direction of seam formation, and a presser yieldingly opposed to said feed-dog and lifted clear of the bead-chain in advance of and by the interposed chain-bead engaged by the feed-dog during the 100 chain-advancing movement of said feed-dog.

9. In a sewing machine having stitch-forming mechanism adapted to attach a bead-chain to a body-material, a work-support, a 105 feed-dog projected through the work-support and provided with two teeth conveniently spaced to receive therebetween during its feeding movement a portion of a bead of the bead-chain disposed upon the work-support 110 in substantially the line of seam formation, a presser yieldingly opposed to said feed-dog and lifted clear of the bead-chain in advance of and by the interposed chain-bead engaged by the feed-dog during the chain-advancing movement of said feed-dog, and means for 115 feeding the body-material with an edge thereof in juxtaposed relation with the bead-chain.

10. In a sewing machine, an endwise reciprocatory and laterally vibratory needle, a 120 work-support, means for guiding the edge of a body-material and a bead-chain past the stitch-forming mechanism in juxtaposed relation upon said work-support and within the range of the lateral vibration of the needle, work-feeding means including a feed-dog engaging the chain-beads successively, and presser-devices opposed to said work-feeding means comprising a presser yieldingly bearing upon the margin of the body- 125 130

material, and an auxiliary-presser yieldingly engaging the bead-chain.

11. In a bead-chain sewing machine, stitch-forming mechanism, a work-support including a throat-plate having a feed-dog slot, work-advancing means including a feed-dog operating through said slot, and a bead-chain guard closing said feed-slot between the rearward end of the feed-dog and the rearward

10 end of said slot.

12. In a bead-chain sewing machine, stitch-forming mechanism, a work-support including a throat-plate having a feed-dog slot, work-advancing means including a feed-dog
15 operating through said slot, and a bead-chain guard comprising a spring-plate closing the gap between the rearward end of the throat-plate slot and the feed-dog yielding to the rising and falling movements of said feed-dog.

20 In testimony whereof, I have signed my name to this specification.

WALTER MYERS.
